CLAIM

The ornamental design for an auxiliary handle for a liquid container, as shown and described.

DESCRIPTION

FIG. 1 is a perspective view of the auxiliary handle for liquid containers showing my new design;

FIG. 2 is a top view thereof;

FIG. 3 is a side elevational view thereof, the opposite side being a mirror image thereof;

FIG. 4 is a front elevational view thereof; and,

FIG. 5 is a rear elevational view thereof.
